UNITED STATES PATENT OFFICE.

RICHARD F. JOYCE, OF HAVERHILL, MASSACHUSETTS, ASSIGNOR TO UNITED SHOE MACHINERY CORPORATION, OF PATERSON, NEW JERSEY, A CORPORATION OF NEW JERSEY.

HEEL-SEAT-FITTING MACHINE.

Application filed April 10, 1924. Serial No. 705,672.

This invention relates to the manufacture of shoes and is illustrated herein as embodied in a heel seat fitting machine arranged to trim surplus material from the peripheral portions of the heel seats of the soles of shoes to prepare the shoes for the attachment of wood heels.

In preparing shoes for the attachment of certain types of heels having concave attaching surfaces, of which wood heels are a well-known and important example, it is necessary to trim away the peripheral portions of the heel seats of the shoes since heels of this type are attached to shoes in such a manner that the edge of the sole is not visible between the heel and the shoe upper. At the same time, the full thickness of the sole is desirable over the greater part of the heel seat area to give strength to the shoe and to contribute to the foundation to which the heel is to be nailed. It is highly desirable that this trimming operation, which is commonly spoken of as heel seat fitting, be performed with precision and that the extent of the trimming operation conform with a considerable degree of exactness to the configuration of the heel seat surface of the heel to be attached.

It is an object of the present invention to provide a machine which will perform the heel seat fitting operation with precision and without danger of injury to the shoes operated upon, and which at the same time shall be simple in construction and easy to operate so that it may be used successfully even by unskilled operators.

With these objects in view, the herein disclosed illustrative machine is provided with a work support arranged to receive a shoe and movable lengthwise of the shoe to present the shoe to a group of rotary cutters arranged upon axes extending lengthwise of the shoe, a pair of the cutters being positioned to operate upon the opposite edges of the heel seat of the shoe, while a third cutter operates upon the rear portion of the heel seat. Co-operating with the work support is a crease plate arranged to enter the rand crease of a shoe to be operated upon to support the marginal portion of the heel seat of the sole of the shoe and to protect the upper of the shoe from injury. This crease plate is made up of a plu-

rality of sections, each of which is movable normally to the periphery of the heel seat of a shoe on the support to bring the sections into and to move them out of engagement with the rand crease of the shoe. Referring still to the herein disclosed illustrative arrangement, the pair of cutters referred to above as positioned to operate upon opposite edges of the heel seat of the shoe is arranged to trim the opposite edges of the heel seat portion of the sole as the shoe is moved lengthwise towards the cutters. These cutters also form the shoulders in the sole against which the breast of the heel is to be positioned, and with this in view the cutters are formed as non-tapered milling cutters. As the shoe is presented to the cutters, the positions of the cutters widthwise of the shoe are automatically adjusted to cause the cutters to follow the contour of the heel seat of the sole. The third cutter, which is provided to trim the rear portion of the heel seat of the sole, is illustrated as a tapered or beveled rotary cutter. Mechanism is provided by which the side cutters are withdrawn from the work when the rear cutter is operating and the rear cutter is withdrawn when the side cutters are operating.

With the above and other objects and features in view, the invention will now be described in connection with the accompanying drawings and pointed out in the claims.

In the drawings,

Fig. 1 is a side elevation of the operating parts of a heel seat fitting machine embodying the present invention;

Fig. 2 is a perspective view showing the work support and the rotary cutters of the machine of Fig. 1, as well as certain associated parts;

Fig. 3 is a transverse section through the work support of the machine, showing also the cutter arrangement;

Fig. 4 is a detail view partly in longitudinal section of the mounting of and operating means for the rear cutter;

Figs. 5 and 6 are perspective views showing the operation of the side and rear cutters respectively;

Fig. 7 illustrates the mode of operation of the rear cutter;

Fig. 8 is a perspective view of mechanism used to control the extent of the trimming operation; and

Fig. 9 illustrates part of the power transmission means of the machine.

The illustrated machine is provided with a column 20 having a head 22 upon which is mounted a standard 24 carrying at its upper extremity a forwardly extending arm 26. A pair of shafts 28, 30 are carried by arm 26, the rear end of each shaft being mounted in swiveled bearings 32 near the rear end of that arm. A pair of supports 34, which are pivotal at 36 (Figs. 1 and 2) to the forward portion of arm 26, are provided with bearings 38 for the forward ends of shafts 28, 30. Arm 26 carries at its forward end a yoke 40 provided with a pair of depending portions in which are formed bearings for a shaft 42. Yoke 40 is rigidly secured to the lower end of a vertical shaft 44 (Fig. 4) having a bearing in the forward end of arm 26 and mounted for both oscillating and endwise movement under the control of a hand lever 46, as will be hereinafter more fully described. Mounted upon the forward extremities of shafts 28, 30 are a pair of non-tapered, rotary milling cutters 48 and 50 each having a plurality of successively operating cutting edges (Fig. 3), while a similar but tapered or beveled rotary cutter 52 (Figs. 3 and 4) is carried by shaft 42, these cutters being arranged to trim the opposite edges and the rear portion respectively of the heel seat of the sole of a shoe which is brought into operative engagement therewith.

Slidably mounted upon the head 22 of the machine is a plate 54 (Figs. 1 and 8) provided with a rack 56 meshing with a gear segment 58 secured rigidly to a hand lever 60 so that movement of lever 60 back and forth will slide plate 54 rearwardly and forwardly upon the head of the machine. Plate 54 carries a platform 62, which in turn carries a group of brackets 64, each provided with a pair of slideways 68, 70 (Fig. 2) arranged to guide and control the inward and outward movement of crease plate members or sections 72, 74, 76, which are arranged to enter the rand crease of the shoe to be operated upon. Platform 62 also carries a short column 78 (Figs. 2 and 3) having upon its upper end a plate 80 provided with a slideway 82 in which is mounted a block 84 carrying a last pin 86. Pivoted to the forward extremity of block 84 is a link 88 which, together with a link 90 pivoted to the forward extremity of plate 80, forms an adjustable support for a toe rest 92. Also carried by platform 62 and mounted for rotary movement relatively thereto is a disk 93 provided with a hand lever 94 by means of which it may be oscillated or rotated through a small angle. Disk 93 is provided with five cam slots 96, each receiving a pin 98 carried by the inner extremity of a plate 100 slidably

mounted in way 70. The inner end of each plate 100 is pivoted to the lower extremity of a lever 102 fulcrumed at 104 to the corresponding bracket 64 and pivoted at its upper extremity to a lug formed upon or connected to the corresponding crease plate section 72, 74 or 76. Thus movement of hand lever 94 will move crease plate sections 72, 74, 76 inwardly or outwardly to bring them into engagement with or out of engagement from the rand crease of a shoe mounted upon a last carried by last pin 86 and having its toe supported on the toe rest 92.

Cutters 48, 50 are arranged, as shown in Fig. 3, to trim the side portions of the heel seat of the sole of a shoe as the shoe upon the work support is moved longitudinally between them, crease plate sections 72, 74, 76 protecting the upper of the shoe and at the same time supporting the margin of the heel seat portion of its sole as the cutters operate. In order that the forward extent of the trimming operation may be properly limited, plate 54 is provided with a support 110 (Figs. 1 and 8) for a heel 112, an abutment 114 being provided to restrain the heel from rearward movement. Slidably mounted upon the support 110 is a gage member 116 adjustable back and forth by means of a screw 118. The heel which is to be attached to the shoe, or another heel of the same size and style, is placed upon support 110 with its rear end in contact with abutment 114 and gage 116 is adjusted into engagement with the breast of the heel. A pair of rods 120 are carried by standard 24 with their forward extremities in a position to limit the rearward movement of the work support by engagement with gage member 116, rods 120 and gage member 116 thus determining the forward extent of the trimming operation in accordance with the length of the heel to be attached.

It is also necessary to control the position of cutters 48 and 50 transversely or widthwise of the shoe to be operated on in order to produce the desired contour of the heel seat portion of the sole. With this in view supports 34 each carry at their lower extremity a roll 130 (Figs. 2 and 5) arranged for engagement with one of a pair of cam members 132 carried by crease plate section 72, a spring 133 anchored at its ends to a pair of pins 134 carried by the supports 34 holding rolls 130 in engagement with cam members 132.

The action of cutters 48, 50, if they alone were used, would leave untrimmed a portion at the extreme rear of the heel seat (see Fig. 5), and it is for the purpose of trimming this portion that cutter 52 is provided. Assuming yoke 40 in its lowered position and the shoe to be operated upon in its rearmost position, sidewise movement, back and forth, of lever 46 will be transmitted to yoke 40 through an upwardly extending arm 140 of the latter and a pin 142 carried by arm 140

and having a working fit in a hole in lever 46.

In order to facilitate the operation of the machine, means is provided for moving cutters 48 and 50 apart widthwise of the shoe 5 when cutter 52 is moved down into operative position and to move cutter 52 upwardly away from the sole of the shoe when cutters 48 and 50 are brought into operative position. For this purpose shaft 44 carries a cap 144 10 connected by a link 146 with a lever 148 to the forward extremity of which lever 46 is fulcrumed for horizontal swinging movement. Lever 148 is connected at its rear end to a link 150 carried by arm 26 and is thus mounted 15 for vertical swinging movement. Cap 144 is also provided with a pair of lugs 152, to which are pivoted a pair of links 154, these links being pivoted respectively to the supports 34 forward of their pivots 36. This 20 construction forms in effect a toggle so that as lever 46 and cutter 52 are moved downwardly, supports 34 and cutters 48, 50 are moved apart and as lever 46 and cutter 52 are moved upwardly, supports 34 and cutters 25 48 and 50 are moved toward each other.

Cutters 48, 50 and 52 may be driven by any suitable gearing. As illustrated the shaft 42, upon which cutter 52 is mounted, has secured to it a beveled gear 160 meshing with a beveled gear 162 mounted upon a stub shaft carried by yoke 40 and having rigidly secured to it a belt pulley 164 (Fig. 4). Passing around pulley 164 is a belt 166 driven from any suitable source of power such as a pulley 30 168, a suitable arrangement of idlers being provided as shown, for example, at 170 (Fig. 9). Shafts 28 also are provided upon their rear ends with belt pulleys 172 around which passes a belt 174 driven from a belt pulley 40 176, suitable idlers being used to cause belt 174 to rotate cutter 48 in a clockwise direction and cutter 50 in a counter-clockwise direction, as viewed in Fig. 3.

In the operation of the machine, the last 45 carrying the shoe upon which the heel seat fitting operation is to be performed is placed upon last pin 86 with the toe of the shoe upon toe rest 92 and lever 94 is operated to bring crease plate sections 72, 74, 76 into the rand 50 crease of the shoe to support the marginal portion of the heel seat of the sole and to protect the upper of the shoe from possible damage. The heel to be attached to the shoe, or one like it, is placed upon heel support 110, 55 and gage 116 is adjusted into engagement with the breast of the heel, as previously described. Then lever 60 is swung rearwardly to move the shoe into operative relation to the cutters. Assuming that cutters 48, 50 have 60 been moved outwardly into inoperative position, when the shoe reaches its rearmost position it will engage cutter 52 which is then in its lowered or operative position. Lever 46 being oscillated once or twice, cutter 52 moves

widthwise of the shoe and trims the rear portion of the heel seat. Then lever 46 is moved upwardly, bringing cutters 48 and 50 inwardly widthwise of the shoe into engagement with opposite edge portions of the sole of the shoe, making the breast cuts, and thus 65 forming the abutments against which the breast of the heel will be positioned. Lever 60 is then swung forwardly, bringing the shoe out of the machine and causing cutters 48 and 50 to trim the opposite edges of the 70 heel seat, the cut made by them merging into the cut made by lever 52 on account of the curvature of cams 132. As an alternative mode of operation, cutters 48 and 50 may be in their inner or operative position and cutter 52 in its elevated or inoperative position 75 while the work support is moved rearwardly, cutters 48 and 50 thus trimming the side portions of the heel seat. Then when the shoe reaches its rearmost position, lever 46 is moved downwardly to move cutters 48 and 50 outwardly to their inoperative position and to move cutter 52 downwardly to its operative position. A back and forth movement 80 of lever 46 then causes cutter 52 to complete its trimming operation.

Having described the invention, what I claim as new and desire to secure by Letters Patent of the United States is:—

1. A heel seat fitting machine having a 95 pair of rotary cutters each having a plurality of successively acting cutting edges arranged to operate simultaneously upon different parts of the edge of the heel seat portion of the sole of a shoe to trim surplus material therefrom.

2. A machine for use in the manufacture of shoes having a pair of milling cutters arranged to operate simultaneously one upon each of the opposite edges of the heel portion 105 of a sole to trim surplus material therefrom.

3. A machine for use in the manufacture of shoes having a pair of milling cutters arranged to operate simultaneously upon opposite edges of the heel portion of a sole to trim surplus material therefrom, and a cutter arranged to trim surplus material from the rear portion of the sole.

4. A heel seat fitting machine having a pair of rotary cutters arranged to operate 115 simultaneously one upon each of the opposite edges of the heel seat portion of a sole to trim surplus material therefrom, and a rotary cutter arranged to trim surplus material from the rear portion of the heel seat of the sole, 120 each of said rotary cutters having a plurality of cutting edges operating in rapid succession on the sole.

5. A machine for use in the manufacture of shoes having a pair of continuously rotated 125 cutters arranged to operate simultaneously upon opposite edges of the heel portion of a sole to trim surplus material therefrom, and

means for causing relative movement of the cutters and the sole in the general direction of the length of the sole.

6. A heel seat fitting machine having a pair 5 of independent cutters arranged to operate simultaneously upon opposite edges of the heel seat portion of a sole to trim surplus material therefrom, and means for moving the sole lengthwise to cause the cutters to operate progressively upon the edges of the heel seat.

7. A machine for use in the manufacture of shoes having, in combination, a pair of crease plate members arranged simultaneously to enter the rand crease of a shoe to support opposite edges of the heel seat portion of the sole of the shoe, and a pair of rotary cutters having their axes of rotation substantially in the direction of the length of a shoe engaged by the crease plates and arranged to trim the edge 20 portions of the heel seat of the sole.

8. A heel seat fitting machine having a pair of rotary cutters arranged to operate simultaneously upon opposite edges of the heel seat portion of a sole to trim surplus material therefrom, means for causing relative movement of the cutters and the sole in the general direction of the length of the sole, and means for controlling the position of the cutters transversely of the sole arranged to cause the 25 cutters to follow the contour of the heel seat of the sole during said relative movement.

9. A heel seat fitting machine having a pair of opposed cutters arranged to operate simultaneously in opposite directions upon opposite 30 edges of the heel seat portion of a sole to trim surplus material therefrom, means for causing relative movement of the cutters and the sole in the direction of the length of the sole to cause the cutters to operate progressively 35 upon the edges of the heel seat portion of the sole, and a third cutter arranged to trim surplus material from the rear portion of the heel seat of the sole.

10. A machine for use in the manufacture of 40 shoes having, in combination, a pair of cutters arranged to operate one upon each of the opposite edges of the heel seat portion of the sole of a shoe to trim surplus material therefrom, means for causing relative movement of the shoe and the cutters in the direction of the 45 length of the shoe to cause the cutters to operate progressively upon the edges of the heel seat, and means for controlling the position of the cutters transversely of the sole arranged to cause the cutters to follow substantially the 50 contour of the heel seat of the shoe during said relative movement.

11. A machine for use in the manufacture of 55 shoes having, in combination, a crease plate arranged to enter the rand crease of a shoe, a pair of cutters arranged to operate one upon each of the opposite edges of the heel seat portion of the sole of a shoe engaged by said crease plate, means for causing relative movement of 60 the shoe and the cutters in the direction of the

length of the shoe to cause the cutters to operate progressively upon the edges of the heel seat, and means for controlling the position of the cutters transversely of the sole arranged to cause the cutters to follow substantially the 70 contour of the heel seat of the shoe during said relative movement.

12. A heel seat fitting machine having, in combination, a work support, a pair of cutters, a crease plate arranged to enter the rand crease 75 of a shoe upon the work support to support the edge of the heel seat portion of the sole of a shoe, means for causing relative movement of the cutters and the shoe in the general direction of the length of the shoe to cause the cutters to trim surplus material from the opposite edges of the heel seat portion of the sole of the shoe, and means for controlling the position of the cutters transversely of the sole of the shoe 80 arranged to cause the cutters to follow the 85 contour of the heel seat of the shoe during said relative movement.

13. A machine for use in the manufacture of 90 shoes having a pair of rotary cutters arranged to operate one upon each of the opposite edges of the heel seat portion of the sole of a shoe to trim surplus material therefrom, means for moving the shoe lengthwise to cause the cutters to operate progressively upon the edges of the heel seat, and a pair of cams for controlling 95 the position of the cutters transversely of the sole arranged to cause the cutters to follow substantially the contour of the heel seat of the sole during said movement of the shoe.

14. A machine for use in the manufacture 100 of shoes having a work support and a tapered rotary cutter with its axis of rotation substantially parallel to the heel seat surface of the sole of a shoe upon the support and extending in the general direction of the length of said 105 shoe, said cutter being arranged to trim surplus material from the rear portion of the heel seat of the sole of a shoe upon the support.

15. A heel seat fitting machine having a 110 crease plate arranged to enter the rand crease of a shoe, and a tapered rotary cutter having its axis of rotation extending in the general direction of the length of a shoe engaged by the crease plate, said cutter being arranged to bevel the rear portion of the 115 heel seat of the sole of the shoe.

16. A heel seat fitting machine having, in combination, a work support, a crease plate arranged to enter the rand crease of a shoe 120 upon the work support to support the edge of the heel seat portion of the sole of the shoe, and a pair of rotary cutters having their axes of rotation substantially in the direction of the length of the shoe upon the work support, and means for moving the work support in the direction of the length of the shoe to cause the cutters to trim the edge portions of the heel seat of the shoe.

17. A heel seat fitting machine having, in combination, one or more crease plate mem- 125

- bers arranged to enter the rand crease of a shoe, a pair of rotary cutters arranged to trim the side portions of the heel seat of the shoe, means for moving the cutters transversely of the shoe to bring them into and out of trimming relation to the sole of the shoe, means for causing relative movement of the shoe and the cutters lengthwise of the shoe to cause the cutters to trim the side portions of the heel seat of the sole of the shoe, and means for controlling the position of the cutters transversely of the shoe during said relative lengthwise movement.
18. A heel seat fitting machine having, in combination, a crease plate arranged to enter the rand crease of a shoe, a pair of rotary cutters arranged to trim the side portions of the heel seat of the shoe, means for moving the cutters transversely of the shoe to move them into and out of trimming relation to the sole of the shoe, means for causing relative lengthwise movement of the shoe and the cutters to cause the cutters to trim the side portions of the heel seat of the sole of the shoe, and a pair of cams carried by the crease plate for controlling the position of the cutters transversely of the shoe during said relative lengthwise movement.
19. A heel seat fitting machine having a work support arranged to carry a shoe the heel seat portion of which is to be trimmed, a yoke pivoted to the frame of the machine, a rotary cutter mounted in the yoke and arranged for engagement with the rear portion of the heel seat of the sole of the shoe, and means for oscillating the yoke transversely of the shoe to cause the cutter to trim the surplus stock from the rear portion of the heel seat of the sole of the shoe.
20. A machine for use in the manufacture of shoes having a pair of cutters to trim the side portions of the heel seat of the sole of a shoe, a cutter to trim the rear portion of the heel seat of the sole of the shoe, and means simultaneously to move the side cutters into trimming relation and the rear cutter out of trimming relation.
21. A heel seat fitting machine having a pair of cutters to trim the side portions of the heel seat of the sole of a shoe, a third cutter to trim the rear portion of the heel seat of the sole of the shoe, and gearing arranged simultaneously to move the side cutters into trimming relation and the rear cutter out of trimming relation and also simultaneously to move the side cutters out of trimming relation and the rear cutter into trimming relation to the sole of the shoe.
22. A heel seat fitting machine having a crease plate arranged to enter the rand crease of a shoe to support the periphery of the heel seat portion of the sole of the shoe, a pair of cutters arranged to trim the side portions of the heel seat of the sole of the shoe, a cutter to trim the rear portion of said
- heel seat, toggle mechanism connected to said cutters, and a lever for operating said toggle mechanism arranged to cause the rear cutter to move into operative position as the side cutters move into inoperative position relative to the sole of the shoe.
23. A heel seat fitting machine having, in combination, a work support, a pair of rotary cutters mounted upon axes extending lengthwise of a shoe upon the support and movable transversely of the shoe into and out of trimming position, the cutters and the work support being arranged for relative movement lengthwise of the shoe to cause the cutters to trim the side portions of the heel seat of the sole of the shoe, and a pair of cams arranged to control the positions of the respective cutters transversely of the shoe during said relative movement.
24. A heel seat fitting machine having a work support, and a rotary cutter with its axis of rotation extending in the general direction of the length of a shoe upon the support, and means for moving the work support lengthwise of the shoe to present to the cutter the rear portion of the heel seat of the sole of a shoe upon the support.
25. A heel seat fitting machine having a work support, a cutter mounted for rotation upon an axis extending in the general direction of the length of a shoe upon the support, means for oscillating the cutter in a path extending substantially transversely of the shoe to cause the cutter to trim the surplus material from the rear portion of the heel seat of the sole of the shoe, and means for moving the cutter toward and from the sole of the shoe to bring it into and out of trimming relation thereto.
26. A machine for use in the manufacture of shoes having a pair of rotary cutters each having a plurality of successively acting cutting edges arranged to trim the opposite sides of the heel seat portion of the sole of a shoe, and means for moving the cutters simultaneously transversely of the sole of the shoe to bring them into and out of trimming relation to said sole.
27. A heel seat fitting machine having a pair of rotary milling cutters mounted upon substantially parallel axes, means for supporting a shoe in operative relation to the cutters, and means for operating the cutters to cause them simultaneously to make heel breast receiving cuts in the sole of a shoe.
28. A heel seat fitting machine having a non-tapered, rotary cutter arranged to trim the heel seat portion of the sole of a shoe, means for continuously rotating the cutter, and means for moving the cutter transversely of the sole of a shoe during its continued rotation to bring it into and out of trimming relation to the sole of the shoe.
29. A heel seat fitting machine having a pair of non-tapered, milling cutters mounted

upon substantially parallel axes, means for supporting a shoe in operative relation between the cutters, and means for moving the cutters toward each other to cause them to make heel breast receiving cuts in the sole 5 of a shoe.

30. A heel seat fitting machine having a pair of cutters, means for rotating said cutters, and means separate from the cutter rotating means for moving the cutters toward each other to cause them to make heel breast receiving cuts in the sole of a shoe positioned between the cutters.

31. A heel seat fitting machine having a work support arranged to carry a shoe, a pair of rotary cutters, means for rotating said cutters, and means for moving the cutters toward each other to cause them simultaneously to enter the sole of a shoe from opposite sides in position to make heel breast receiving cuts.

32. A heel seat fitting machine having a work support arranged to carry a shoe, a pair of cutters mounted for rotation about axes extending lengthwise of a shoe upon the support, means for continuously rotating said cutters, and means for moving the cutters toward each other to cause them simultaneously to enter the sole of a shoe from opposite sides to make heel breast receiving cuts.

33. A heel seat fitting machine having, in combination, a crease plate arranged to support the periphery of the heel seat portion of the sole of a shoe, a pair of rotary cutters, means for rotating said cutters, and means for moving the cutters toward each other to cause them to enter the material of the sole from opposite sides to make heel breast receiving cuts.

34. A heel seat fitting machine having, in combination, a work support, a crease plate arranged to support the periphery of the heel seat portion of the sole of a shoe upon the support, a pair of milling cutters mounted for rotation upon axes extending lengthwise of a shoe upon the support, and means for moving the cutters toward each other to cause them to enter the material of the sole of a shoe from opposite sides to make heel breast receiving cuts.

35. A heel seat fitting machine having a crease plate arranged to enter the rand crease of a shoe to support the edge of the heel seat portion of the sole of the shoe during the heel seat fitting operation, said crease plate being made up of a plurality of sections, each section being adjustable substantially normally to the periphery of the heel seat portion of the sole of the shoe and a lever connected to the crease plate sections and arranged when rocked to move said sections.

36. A heel seat fitting machine having a crease plate arranged to enter the rand crease

of a shoe to support the edge of the heel seat portion of the sole of the shoe substantially from one end of the heel breast line, around the rear of the heel seat to the other end of the heel breast line, during the heel seat fitting operation, said crease plate being made up of a plurality of sections, crease plate sections at the opposite sides of the heel seat portion of the sole and a crease plate section at the rear being adjustable substantially normally to the periphery of said heel seat portion and manually operated means for adjusting said crease plate sections.

37. A heel seat fitting machine having a crease plate arranged to enter the rand crease at the rear of the shoe, a slide in which the crease plate is mounted for rectilinear movement toward and from the position of the rand crease of the shoe to be operated upon, and a hand lever for moving the crease plate in the slide.

38. A heel seat fitting machine having a crease plate section, a slide in which the crease plate section is mounted for rectilinear movement toward and from the position of the rand crease of the shoe to be operated upon, said slide being stationary relatively to the shoe being operated upon, and manually operable means for moving the crease plate in the slide.

39. A heel seat fitting machine having a work support, a crease plate made up of a pair of sections, one upon each side of a shoe, arranged to enter the rand crease of a shoe upon the work support to support the margin of the heel seat portion of the sole of the shoe at the opposite edges of the heel seat and another section arranged to enter the rand crease at the rear of the shoe to support the rear portion of the sole, and means for moving said crease plate sections substantially normally of the periphery of the heel seat portion of the sole toward and into the rand crease of the shoe upon the support.

40. A heel seat fitting machine having a crease plate arranged to enter the rand crease of a shoe to support the marginal portion of the heel seat of the sole of the shoe during the heel seat fitting operation, a cam member, and a lever connected at one end to the crease plate and at the other end to the cam member to move the crease plate in or out as the cam member is moved.

41. A heel seat fitting machine having a crease plate made up of a pair of sections, one upon each side of a shoe to be operated upon, arranged to enter the rand crease of the shoe to support the margin of the heel seat portion of the sole at the opposite edges of the heel seat and another section arranged to enter the rand crease at the rear of the shoe to support the rear portion of the sole, and means for moving the crease plate sections which engage the opposite edges of the

sole substantially in a straight line toward and into the rand crease of the shoe to be operated on.

42. A heel seat fitting machine having a crease plate made up of a plurality of sections arranged to enter the rand crease of a shoe to support the peripheral portion of the heel seat of the sole of the shoe, and means for adjusting said plate sections substantially normally of the periphery of the heel seat of the sole comprising a member having a series of cam slots and connections from each cam slot to one of the crease plate sections arranged to adjust the crease plate sections simultaneously in or out as may be desired, in accordance with the size of the shoe to be operated upon.

43. A heel seat fitting machine having a crease plate made up of a plurality of sections arranged to enter the rand crease of a shoe to support the peripheral portion of the heel seat of the sole of the shoe, and means for adjusting said crease plate sections substantially normally of the periphery of the heel seat of the sole comprising a disk having a series of cam slots, means for rotating said disk, and connections from each cam slot to one of the crease plate sections so as to adjust the crease plate sections simultaneously in or out as the disk is rotated.

44. A heel seat fitting machine having, in combination, a work support, a cutter, means for moving the work support in a straight line toward the cutter to cause the cutter to trim surplus material from the periphery of the heel seat of the sole of the shoe upon the work support, a heel support connected to and movable with the work support, an abutment carried by the heel support and arranged to engage one end of a heel, a gage adjustably carried by the heel support for movement into engagement with the other end of the heel, and a stop arranged in the path of movement of the gage to limit the movement of the work support toward the trimming means and thus to control the extent of the heel seat fitting operation.

45. A heel seat fitting machine having, in combination, a work support, a group of rotary cutters, means for moving the work support toward the cutters to cause the cutters to trim surplus material from the periphery of the heel seat of the sole of the shoe upon the work support, a heel support connected to and movable with the work support, an abutment carried by the heel support and arranged to engage one end of a heel, a gage adjustably carried by the heel support for movement into engagement with the other end of the heel, and a stop arranged in the path of movement of the gage to limit the movement of the work support toward the trimming means and thus to control the extent of the heel seat fitting operation.

46. A heel seat fitting machine having, in

combination, means for trimming the peripheral portion of the heel seat of a shoe, a work support arranged to carry the shoe to be operated upon and movable toward and from the trimming means, a heel support arranged to receive a heel similar to that which is to be attached to the shoe and to restrain lengthwise movement of the heel in one direction, a gage member adjustably carried by the work support and arranged for engagement with the heel upon the support, and a stop positioned in the path of movement of said gage member to limit the movement of the work support toward the trimming means so as to control the forward extent of the trimming operation.

47. A heel seat fitting machine having, in combination, means for trimming the peripheral portion of the heel seat of a shoe, a work support arranged to carry the shoe to be operated upon and movable toward and from the trimming means, a heel support movable with the work support and arranged to receive a heel similar to that which is to be attached to the shoe, a gage member adjustably carried by the work support and arranged for engagement with the heel upon the support, and a stop positioned in the path of movement of said gage member to limit the movement of the work support toward the trimming means so as to control the extent of the trimming operation.

48. A heel seat fitting machine having, in combination, a jack having a pin arranged to enter the thimble of a last, a rotary cutter arranged with its axis of rotation substantially parallel to the heel seat surface of the sole of a shoe on a last carried by the jack, means for rotating said cutter, and means for causing relative bodily movement of the jack and the cutter to cause the cutter to trim surplus stock from the heel seat of the sole of a shoe on the jack.

49. A heel seat fitting machine having, in combination, a substantially flat crease plate arranged to enter the rand crease of a shoe, a rotary cutter having a plurality of successively operating cutting edges arranged with its axis of rotation substantially parallel to the heel seat surface of the sole of a shoe positioned by said crease plate, said cutter and crease plate being relatively positioned so that by relative movement of said shoe and the cutter along a path peripherally of the rear portion of the sole of the shoe the cutter will trim surplus stock from the rear portion of the sole of the shoe, and means for causing relative movement of the shoe and the cutter along a path peripherally of the rear portion of the sole of the shoe.

50. A heel seat fitting machine having, in combination, a crease plate arranged to enter the rand crease of a shoe to hold the shoe during the heel seat fitting operation, a cutter, means for causing relative movement of the

cutter and the shoe to cause the cutter to trim surplus material from the peripheral portion of the heel seat of the shoe thus held, and a guide member carried by the crease plate to control said relative movement.

51. A heel seat fitting machine having, in combination, a plurality of crease plates arranged to enter the rand crease of a shoe to grip the shoe during the heel seat fitting operation, guide members carried by the crease plates, and means for trimming surplus material from the peripheral portion of the heel seat of the shoe thus gripped arranged for movement under the control of said guide members.

52. A crease plate for a heel seat fitting machine having a thin edge arranged to enter the rand crease of a shoe and a guide surface carried by said crease plate substantially parallel to said edge to control the fitting operation.

53. A heel seat fitting machine having a pair of cutters arranged to operate one upon each of the opposite edges of the heel portion of a sole to trim surplus material therefrom, means for causing relative movement of the cutters widthwise of the sole, and means for causing relative movement of the cutters and the sole in the general direction of the length of the sole.

54. A heel seat fitting machine having a pair of cutters, means for causing relative movement of the cutters and a shoe in the general direction of the length of the shoe to cause the cutters to operate simultaneously upon the opposite edges of the heel portion of the sole of the shoe to trim surplus material therefrom, and a third cutter arranged for movement widthwise of the shoe to trim surplus material from the rear portion of the sole.

55. A heel seat fitting machine having a pair of crease plates arranged to enter the rand crease of a shoe to support the edge of the heel seat portion of the sole of the shoe, a pair of rotary cutters, means for rotating the cutters in opposite directions, and means for causing relative movement of the crease plates and the rotary cutters substantially lengthwise of the shoe thereby causing the cutters to trim surplus material from the opposite edges of the heel seat of the sole of the shoe.

56. A heel seat fitting machine having a pair of cutters arranged to operate upon opposite edges of the heel seat portion of a sole to trim surplus material therefrom, means for causing relative movement of the cutters and the sole in the general direction of the length of the sole, and means for controlling the position of the cutters transversely of the sole arranged to cause the cutters to follow the contour of the heel seat of the sole during said relative movement.

57. A heel seat fitting machine having, in

combination, a pair of cutters for trimming surplus material from the opposite edges of the heel seat of the sole of a shoe a jack having a last-supporting pin, said jack being slidably mounted for movement into operative position between said cutters, and means for moving said jack and a shoe and last carried thereby toward and away from said cutters.

58. A heel seat fitting machine having, in combination, a work support arranged to carry a shoe to be operated upon, a pair of cutters arranged to operate on opposite sides of the heel seat of the sole of the shoe to trim surplus material therefrom, a rack connected to the work support, a gear segment meshing with said rack, means for rotating said gear segment to move the work support into and out of operative relation to the cutters, a gage member arranged to limit the movement of said work support, and a screw arranged to adjust said gage.

59. A heel seat fitting machine having a support for a shoe, a rotary cutter having a plurality of cutting edges each having a path of movement, as the cutter is rotated, extending through the substance of the sole of a shoe carried by said support between its tread surface and its attaching surface in a substantially oblique direction, and means for moving the cutter widthwise of the sole as the cutter operates on the sole.

60. A heel seat fitting machine having a crease plate arranged to enter the rand crease of the sole of a shoe to support the edge portion of the sole, a rotary cutter having a plurality of cutting edges arranged to operate successively upon the sole of a shoe to trim surplus material from a part of the periphery of the heel seat portion of the sole of a shoe the rand crease of which is engaged by the crease plate and to form a heel breast receiving shoulder at the heel breast line of the sole of the shoe, and means for moving the cutter widthwise of the sole of a shoe during the performance of a part of the heel seat fitting operation.

61. A heel-seat fitting machine having a work support arranged to hold a shoe stationary while it is operated upon, a continuously rotated cutter, and means for moving the cutter substantially transversely of the sole of the shoe at the heel-breast line to cause the cutter to form a heel-breast-receiving shoulder at the breast line of the sole of the shoe.

62. A heel-seat fitting machine having, in combination, a work support arranged to hold a shoe stationary while it is operated upon, a continuously rotated cutter having its axis of rotation extending in the general direction of the length of a shoe upon the work support, and means for moving the cutter transversely of the sole of the shoe at its heel-breast line to cause the cutter to form

a heel-breast-receiving shoulder at the breast line of the sole of the shoe.

63. A heel-seat fitting machine having, in combination, a work support arranged to be held stationary while a shoe mounted on the support is operated on, a crease plate arranged to enter the rand crease of a shoe upon the support to support the marginal portion of the sole of the shoe and to protect the upper of the shoe from possible injury, a continuously rotated cutter, and means for moving the cutter substantially transversely of the sole of the shoe at the heel-breast line of the sole to cause the cutter to form a heel-breast-receiving shoulder at the heel-breast line of the sole.

64. A heel-seat fitting machine having, in combination, a work support arranged to hold a shoe stationary while the shoe is operated upon, a continuously rotated cutter, means for moving the cutter substantially transversely of the sole of the shoe at its heel-breast line to cause the cutter to form a heel-breast-receiving shoulder at the breast line of the sole, and means for trimming surplus material from the rear portion of the sole.

65. A heel-seat fitting machine having, in combination, a work support arranged to hold a shoe stationary while the shoe is operated upon, a continuously rotated cutter, means for moving the cutter substantially transversely of the sole of the shoe at its heel-breast line to cause the cutter to form a heel-breast-receiving shoulder at the breast line of the sole, and a continuously rotated cutter

arranged to remove surplus material from and to bevel the rear portion of the sole.

66. A heel-seat fitting machine having a work support arranged to hold a shoe stationary while it is operated upon, a continuously rotated cutter, means for moving the cutter substantially transversely of the sole of a shoe on the support at the heel-breast line of the sole to form a heel-breast-receiving shoulder, and means for gaging the heel which is to be attached to the shoe or another heel like that heel arranged to control the relative position of the cutter and the shoe lengthwise of the shoe to cause the heel-breast-receiving shoulders to be located at the correct position lengthwise of the shoe.

67. A heel-seat fitting machine having a work support arranged to hold a shoe stationary while it is operated upon, a continuously rotated cutter, means for moving the cutter substantially transversely of the sole of a shoe on the support at the heel-breast line of the sole to form a heel-breast-receiving shoulder, a gage member arranged to be moved into engagement with the heel which is to be attached to the shoe or another heel like that heel, and connections between the gage member and the cutter arranged to control the relative position of the cutter and the shoe lengthwise of the shoe to cause the heel-breast-receiving shoulder to be located at the correct position lengthwise of the shoe.

In testimony whereof I have signed my name to this specification.

RICHARD F. JOYCE.
